Attorney

UNITED STATES PATENT OFFICE

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND

TWISTER RING AND TRAVELER

Application filed August 17, 1929. Serial No. 386,708.

My invention relates to twister rings of the vertical type and to travelers adapted to cooperate therewith.

The essential objects of my invention are 5 to reduce the friction of the traveler upon the ring; to prevent lateral cramping of the traveler in its course; and to afford a free delivery of the lubricant from the ring to the traveler.

10 To the above ends essentially my invention consists in the means for accomplishing the above objects.

In the accompanying drawings which form a part of this specification

15 Figure 1 is a perspective view of my ring and my traveler mounted thereon,

Figure 2, a diametrical section of the ring showing the traveler in side elevation engaging a thread, and

20 Figure 3, a fragmentary section of a ring carrying a modified form of traveler.

Like reference characters indicate like parts throughout the views.

In the drawings 4 represents a twister ring 25 comprising a vertical annular body 5 having annular transversely rounded upper and lower bearing edges 6 and 7, and provided with a transversely arcuate concave annular inner face 8 extending completely from one bearing edge to the other.

Slidably mounted upon the ring is a ring traveler 9 of the vertical type formed from a flat oblong metal strip comprising a straight flat vertical shank 10, slightly longer than 35 the height of the ring, with its lower and upper outer end portions in running contact with the bearing edges 6 and 7 of the ring; an upwardly and outwardly directed arcuate horn or foot 12 upon its lower end also engaging the lower bearing edge 7 upon which it may pivot outwardly and inwardly; and an outwardly and downwardly directed horn 14 integral with the upper extremity of the shank.

40 In operation the thread 16 extending from the delivery rolls to the bobbin propels the traveler annularly upon the ring. The traveler, because of the peculiar ring construction, has during its annular travel a minimum frictional contact therewith, and at only two

points, whereby the dangers of excessive heat and speedy wear of the traveler is lessened.

The lateral tilting of the traveler is absent because the foot 12 of the latter is pivoted upon the lower bearing edge of the ring rather than upon an intermediate or substantial portion of the ring, which pivotal relation of the horn 12 is rendered possible by the concave form of the ring.

45 The extended arcuate concave form of the inner face of the ring affords a perfectly free and unimpeded delivery of the lubricant from the face to the lower annular bearing 7 where a maximum of friction occurs.

In cases where a thread of unusually great 50 diameter is employed the form of traveler shown in Figure 3 is preferable. This differs from the form shown in the other figures merely in that an inwardly directed horizontal loop 18 upon the upper end of the shank 55 10 forms the lower portion of the upper horn, and the outer extremity of the latter 19 is elongated.

I claim:

55 A twister ring comprising a vertical annular body having bearing portions at the top and bottom thereof, the inner face of said body extending in an arc continuously between the top and bottom edges of said ring and being transversely concaved and unobstructed.

60 In testimony whereof I have affixed my signature.

GEORGE H. GILLIGAN.
